Ferry Williams

UNITED STATES PATENT OFFICE.

MOSES WHITE OLIVER, OF LAWRENCE, MASSACHUSETTS.

RAILWAY-RAIL SUPPORT.

SPECIFICATION forming part of Letters Patent No. 426,050, dated April 22, 1890.

Application filed May 4, 1889. Serial No. 309,619. (No model.)

To all whom it may concern:

Be it known that I, MOSES WHITE OLIVER, of Lawrence, in the county of Essex and State of Massachusetts, have invented a new and useful Improvement in Railway-Rail Supports, of which the following is a specification.

This invention relates to railway-rail supports situated usually at the joints or meeting ends of the rails and sometimes termed "joint-fastenings;" and the invention has for its principal objects, first, to concentrate the weight borne by a passing wheel at the point midway between the meeting ends of the rails and midway between the cross-ties next the joint, thus distributing the weight equally upon said cross-ties; second, to cause as nearly as possible an equal deflection of the rails at the instant that the wheel passes the joint, and, third, to clamp the rails in such a manner as to make a joint-fastening.

In the accompanying drawings, in which similar letters of reference indicate like parts, Figure 1 is a plan or top view illustrating my invention. Fig. 2 is a central longitudinal vertical section. Fig. 3 is a cross vertical section taken on line x , Fig. 1. Fig. 4 is a perspective view of the plate E below described. Fig. 5 is a plan of the central portion of the inner end of the plate D' below described.

30 A A represent the rails. B B are the cross-ties next the joint or meeting ends of the rails.

C is a fish-plate, and C' a base-plate, the two being united by a connection C'', which conforms substantially to the shape of the rail. The base C' has two extensions C''' and C''', through which spikes may be driven into the cross-ties. The base-plate C', fish-plate C, and connection C'' are all integral, so that practically the fish-plate extends down

40 and forming a base-plate underlaps the rail.

D is a fish-plate, and D' a base-plate, the two being united by a connection D'', which conforms substantially to the shape of the rail. The base D' has an extension D''', through which spikes may be driven into the cross-tie. The base-plate D', fish-plate D, and connection D'' are all integral, so that practically the fish-plate extends down and forming a base-plate underlaps the rail above the

50 base-plate C'.

E is a bearing-plate placed centrally upon

the base-plate D' and beneath the rails at the joint. This bearing-plate E is comparatively short, while the base-plates C' D' are long, reaching from the outer edge of one cross-tie 55 to the outer edge of the cross-tie on the opposite side of the joint. Thus it will be seen that the rail bears at its joint directly upon the bearing-plate E, the bearing-plate E bearing upon the base-plate D' and the base-plate 6c D' upon the base-plate C'.

E' is a lip on the bearing-plate E, which fits into a notch d in the base-plate D', whereby the plate E is held in its proper place.

H H are spike-holes, and I J are the ordinary bolts and nuts for bolting the fish-plates and rails together.

By means of the above-described construction the weight borne by a passing wheel does not first bear upon one cross-tie, beginning 65 with one edge thereof, and then the other cross-tie, thus causing rocking of the cross-ties, but is sustained squarely by both ties at once, as the weight of said wheel is borne midway between the cross-ties and midway 70 between the meeting ends of the rails, and is thus equally and evenly distributed between the cross-ties, and as the bearing-plate is narrower than the base-plates and the base-plates extend across the entire surface of both cross- 75 ties.

If desired, one of the base-plates may be omitted without interfering with the spirit of the invention.

The base-plates and fish-plates may extend 80 over more than one span between cross-ties, if desired.

Having thus fully described my invention, what I claim, and desire to secure by Letters Patent, is—

The combination of the rail or rails A, bearing-plate E, provided with the lip E', integral fish-plate and base-plate D D' D'' D''', provided with the notch d, and integral fish-plate and base-plate C C' C'' C''' C''', combined 90 and constructed substantially as and for the purpose set forth.

MOSES WHITE OLIVER.
